UNITED STATES PATENT OFFICE.

ZADOK T. BLACKWELL, OF CARRINGTON, MISSOURI.

CLUTCH-WHEEL.

SPECIFICATION forming part of Letters Patent No. 245,769, dated August 16, 1881.

Application filed June 23, 1881. (No model.)

To all whom it may concern:

Be it known that I, ZADOK T. BLACKWELL, of Carrington, in the county of Callaway and State of Missouri, have invented an Improved 5 Clutch - Wheel, of which the following is a specification.

The object of my invention is to provide a new pulley-wheel for rope transmission, which wheel is so constructed that the rope cannot 10 slip thereon.

In the accompanying drawings, Figure 1 is a longitudinal elevation of my improved clutch-wheel. Fig. 2 is a horizontal sectional view of the same. Fig. 3 is a detail perspective view 15 of one of the clutches.

Similar letters of reference indicate corresponding parts.

A series of pairs of clutches, A, are pivoted to the ends of strips B on the sides of a wheel, 20 C, or the lower ends of these clutches are pivoted in short notches or recesses in the edge of the wheel. The inner or adjoining edges of these clutches are curved from the base upward and outward, and are provided with shoulders or offsets E, which shoulders or 25 offsets overlap each other, the clutches being provided with recesses D in the sides to receive the shoulder of the opposite clutch, as shown in Fig. 2. The driving-rope or round

belt F passes around the wheel C and rests in 30 between the clutches A A, and on the shoulders E or directly above them. If the rope F presses on the shoulders E, the two jaws are forced together and the rope is jammed in between the edges of the clutches and held by 35 the same. As soon as the pressure of the rope on the shoulders E ceases the clutches can be easily separated and the rope can pass from between them. It is evident that the rope cannot slip, and thus all the friction is avoided 40 which is produced when a rope is coiled around a drum several times to avoid slipping, as has been customary heretofore. The lower ends of the clutches strike against the shoulders of the wheel or of the blocks or arms to which 45 they are pivoted to prevent them from spreading too far.

Having thus described my invention, I claim as new and desire to secure by Letters Patent—

In a clutch-wheel, the clutches A, constructed 50 substantially as herein shown and described, with shoulders E and a recess, D, as and for the purpose set forth.

ZADOK T. BLACKWELL.
